UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

PROTECTION OF RESISTORS OF ELECTRIC FURNACES.

Application filed April 21, 1921. Serial No. 463,220.

To all whom it may concern:

Be it known that I, GEORGE M. LITTLE, a citizen of the United States, and a resident of Pittsburgh, in the county of Allegheny and State of Pennsylvania, have invented a new and useful Improvement in Protection of Resistors of Electric Furnaces, of which the following is a specification.

My invention relates to electric-resistance furnaces and particularly to carbonaceous resistors for such furnaces and it has for its object to provide means for protecting such carbonaceous resistors against the oxidizing effect of air entering the furnace chamber.

As is well known in the electric furnace art, carbonaceous resistor elements, when operated at relatively high temperature in the open air, are rapidly oxidized thereby and, if left unprotected, will disintegrate very rapidly. Protection for carbonaceous resistor elements has sometimes been afforded by providing them with envelopes of some non-oxidizing material, such as carborundum or silicon carbide. Since the resistor elements are thus made relatively bulky and hard to repair quickly, it is desirable that a more simple protective means be employed.

In practicing my invention, I provide a lamp burning an inflammable oil and permit the flame to burn with an insufficient supply of air, thus causing a smoky flame and the generation of sooty vapors. These vapors are permitted to enter the furnace chamber and to impinge upon the carbonaceous resistor and be deposited thereon. Some of the sooty vapors will strike the walls of the furnace chamber and be deposited thereon.

The single figure of the drawing is a view, in vertical cross section, of an electric furnace comprising the device embodying my invention.

An electric furnace 10 comprises an outer metallic frame work 11 provided with suitable supports 12. An outer lining 13 comprises suitable heat-insulating bricks or blocks located within the framework or casing 11. An inner layer 14 of high-temperature refractory bricks or blocks is provided within the lining 13 and the bricks are suitably spaced apart to form a furnace chamber 15.

A resistor 16 comprises a plurality of car-

bonaceous elements, this resistor being substantially of the type described in a co-pending application, Serial No. 454,776, filed by me, March 23, 1921, and assigned to the Westinghouse Electric and Manufacturing Company.

An opening 17 is provided at the front of the furnace substantially at the bottom of the chamber 15 to permit of introducing metallic articles into the chamber to be heated by the resistor.

At the back of the furnace, is provided a suitable opening 18 through the wall in which is removably located a tube 19. At the outer end of the tube 19 is located a depending elbow member 20, both the members 19 and 20 being of relatively large diameter and being easily and quickly removable from their operative positions.

A lamp 21 is mounted on a suitable supporting member 22, carried by the supports 12. The lamp 21 may be of any suitable size and shape to hold a supply of inflammable oil. A member 23, here indicated as of inverted saucer-shape, is adjustably mounted on the lamp 21 to permit of regulating the supply of air to the flame of the lamp. It may be noted that, by so rotating the member 23 on the cooperating threaded stem 24 as to move it upwardly, less air is permitted to reach the flame of the lamp, thus causing a greater amount of sooty vapor.

The sooty vapor generated by the lamp 21 enters the elbow member and flows into the furnace chamber 15 through the tube 19. By reason of the tendency of the incoming gases to flow toward the upper part of the chamber the sooty vapor is carried upwardly and strikes the resistor element as well as the inner surface of the lining 14 and the soot is deposited thereon. The deposited soot protects the elements of the resistor 16 against the oxidizing effect of air which may leak through the opening 17 or past the outside of the tube 19 in the opening 18, the oxidizing effect of the air being expended upon the sooty covering instead of on the resistor elements. By continuously providing a sufficient amount of sooty vapor, the resistor 16 may be protected completely against the oxidizing effect of the air.

In case the elbow 20 and the tube 19 become clogged by deposits of soot, they may

be easily and quickly removed, disassembled, cleaned, and then replaced without interfering with the continuous operation of the furnace itself.

5 It may be noted that the device embodying my invention provides relatively simple means for causing a sooty vapor to be continuously deposited upon the surface of a carbonaceous resistor to protect the same 10 against oxidization.

Various modifications may be made in the device embodying my invention without departing from the spirit and scope thereof and I desire that only such limitations shall 15 be placed thereon as are imposed by the prior art or are specifically set forth in the appended claim.

I claim as my invention:

In an electric furnace, the combination with a housing enclosing a furnace chamber 20 and having an opening near the bottom of said chamber for introducing material to be heated, and a carbonaceous resistor located near the top of said chamber, of a source of hydrocarbon vapor comprising an oil flame, 25 means for conducting the products of combustion of said flame into said chamber near the bottom thereof and means for varying the amount of hydrocarbon vapor produced by said flame.

30 In testimony whereof, I have hereunto subscribed my name this 11th day of April, 1921.

GEORGE M. LITTLE.
